Des. 1675

John W. Burt of New York, N. Y.
Letters Patent No 1675 - Dated Decr 9. 1862.

The schedule referred to in these Letters Patent and making part of the same -

To all whom it may concern:

Be it known that I, John W. Burt of the City, County and State of New York, have produced a new and ornamental Design for Anklet; and I do hereby declare that the following is a full, clear and exact description of the same reference being had to the accompanying drawing making a part of this specification, in which, Figure 1. represents a face view of my invention when spread out to its full extent. -

Figure 2. is a side elevation of the same, when applied to a leg. -

Similar letters of reference in both views indicate corresponding parts. -

This design consists in the application to the side of the anklet of a seam representing false button-holes connected

Dec. 1675

by zigzag line, the alternate corners of which coincide with the ends of the false button-holes whereas the remaining corners are situated between said false button-holes in combination with buttons placed on the ends of the button-holes, the whole being arranged as to produce a new and ornamental design, —

To enable others skilled in the art to fully understand my design, I will proceed to describe it with reference to the drawings, —

The Anklet A, is cut out of enamel, led or "patent" leather in the usual form with four or more points a, and it is fastened to the leg by means of clasps b, which are secured to the anklet by india-rubber bands c, so that said fastenings will permit the anklet to adjust itself to legs of different size, — The anklet is attached to the leg so that the clasps are situated on the inside of the leg and that portion of each anklet, which is situated on the outside of the leg when the anklet is attached to the same, or which is exactly in the middle between the clasps is ornamented by a seam B, —

— which represents a series of false button-holes d, connected by a zigzag line e. This line commences at the left hand end of the upper false button-hole, and it terminates at the left-hand end of the lowest false button-hole, and its corners f, f' are alternately situated between the false button-holes, and then again on the left-hand ends of said button-holes, as clearly shown in both views of the drawing. — Those corners of the zigzag line which coincide with the ends of the false button-holes, are occupied by buttons e, —

The seam B, is made with silk thread of white or any other light color, so that the same can be clearly distinguished from the dark surface of the leather constituting the body of the anklet, and the buttons are made of white porcelain or other light colored material which will produce a contrast with the dark surface of the leather from which the anklet is made, — when the anklet is applied to the leg the buttons C and false button-holes d make it appear as if the same was buttoned on the outside,

Dec. 1675

and at the same time by having the clasps on the inside the operation of attaching and detaching the Anklet is considerably facilitated.

Without the buttons and seam on the outside the anklet when applied to a leg looks plain and unattractive, whereas by the application of this seam and the buttons the appearance of the same is much improved, —

Having thus fully described my Design, what I claim as new, and desire to secure by Letters Patent, is, An anklet A, ornamented by buttons C and a seam B, representing false button-holes 2 connected by a zigzag line e as shown and described, —
